UNITED STATES PATENT OFFICE.

MATTHEW O. TROY, OF SCHENECTADY, NEW YORK, ASSIGNOR TO GENERAL ELECTRIC COMPANY, A CORPORATION OF NEW YORK.

CONTROLLING-SWITCH FOR TRANSFORMERS.

No. 851,786.

Specification of Letters Patent.

Patented April 30, 1907.

Application filed June 22, 1906. Serial No. 322,871.

To all whom it may concern:

Be it known that I, MATTHEW O. TROY, a citizen of the United States, residing at Schenectady, county of Schenectady, State of New York, have invented certain new and useful Improvements in Controlling-Switches for Transformers, of which the following is a specification.

My invention relates to switching devices for transformers, and particularly for step-down transformers inserted between high-voltage supply circuits and low voltage translating devices, such as motors. With such a combination it has ordinarily been the practice heretofore to provide only a single control-switch arranged to disconnect the motor from the transformer secondary. In many cases, as, for instance, in factories or other buildings where the underwriters' rules forbid bringing the high tension wires inside the building, the transformers must be installed outside the building, and the secondary leads alone carried inside. Even where the primary circuit of the transformer is accessible, it is not ordinarily commercially practicable to employ a switch between the transformer primary and the supply-circuit adapted to be opened under load, since such a switch, having to be designed for high voltage, would ordinarily be very costly. On the other hand, if a switch were provided on the high-tension side of the transformer adapted to open the circuit on no-load only, there would be danger that the operator might open this switch before opening the switch on the low-tension side of the transformer, which might result in the destruction of the high-tension switch. Consequently, it has been the practice heretofore to omit switches from the primary circuit of the transformer and to connect the transformer primary directly to the supply circuit through high-tension fuses or other protective devices. With such an arrangement the transformer is at all times connected to the supply circuit, and consequently carries a magnetizing current when the motor is not in operation. This magnetizing current results in a core loss which may considerably impair the all-day efficiency of the combination, particularly if the motor operates for only a small portion of the day.

My invention consists in providing an automatic switch in the primary circuit con-

trolled by the switch in the secondary circuit of the transformer. By making the operation of one switch automatic the attendant is required to operate only one switch, so that the other switch may be placed any desired distance away, and by properly arranging the automatic control, the desired sequence of operation is secured, so that the high-tension switch may be arranged to open and close on no-load only; thereby permitting the use of a cheap construction.

My invention will best be understood by reference to the accompanying drawing, which shows diagrammatically control switches for a transformer and motor arranged in accordance with my invention.

In the drawing, A represents an alternating-current translating device, which is illustrated as an induction motor of the squirrel-cage type; B represents the high-tension supply conductors for the motor, C represents a three-phase step-down transformer inserted between the motor and supply conductors; D represents a switch connecting the motor to the transformer secondary; and E represents a switch connecting the transformer primary to the supply-conductors. The switch E is provided with a tension-spring *e* or other suitable means to return it to open position, and with a magnet winding *F* for closing it. The magnet winding *F* is supplied with current from any suitable source, such as an auxiliary transformer *G*, and is controlled by auxiliary contacts *f*, which are controlled by the switch *D*. When the switch *D* is moved toward closed position, before it closes any of its main contacts it bridges the contacts *f*, thereby energizing magnet winding *F* and closing switch *E*.

The switch *D* is shown arranged to connect the motor to a portion only of the secondary member of the transformer for starting, and then to connect it across the terminals of the transformer for running. The particular arrangement of this switch forms no part of my invention, which is applicable to any type of switch arranged for any desired circuit conditions. Since the contacts *f* are closed before the main contacts of switch *D* are closed and are not opened until after the main contacts of the switch *D* are opened, switch *E* closes and opens only on no-load, and consequently need not be of expensive construction. Furthermore, since the operation of

switch E is entirely automatic, the proper sequence of operation of the switches D and E is secured without requiring any attention from the operator.

5 I do not desire to limit myself to the particular construction and arrangement of parts here shown, but aim in the appended claims to cover all modifications which are within the scope of my invention.

10 What I claim as new and desire to secure by Letters Patent of the United States, is,

1. In combination, a supply circuit, a transformer, a translating device, a switch adapted to connect the transformer primary to the supply-circuit, a second switch adapted to connect the transformer secondary to the device, and means for operating one of said switches automatically when the other switch is operated.

20 2. In combination, a supply circuit, a transformer, a translating device, a switch adapted to connect the transformer primary to the supply circuit, a second switch adapted to connect the transformer secondary to the device, and automatic operating means for one switch controlled by the opening and closing of the other switch.

30 3. In combination, a supply circuit, a transformer, a translating device, a switch adapted to connect the transformer primary to the supply circuit, a second switch adapted to connect the transformer secondary to the device, and electromagnetic operating means for one switch controlled by contacts controlled by the other switch.

35 4. In combination, a supply circuit, a transformer, a translating device, a switch adapted to connect the transformer primary to the supply circuit, a second switch adapted to connect the transformer secondary to the device, a magnet winding for operating one switch, and contacts in circuit with said magnet winding controlled by the other switch.

45 5. In combination, a supply circuit, a transformer, a translating device, a switch

adapted to connect the transformer primary to the supply circuit, a second switch adapted to connect the transformer secondary to the device, a magnet winding adapted to close one switch, and means for energizing said magnet upon the closing of the other switch.

6. In combination, an alternating current motor, a supply circuit therefor, a transformer inserted between the motor and supply circuit, a switch for disconnecting the motor from the transformer, and means for automatically disconnecting the transformer from the supply circuit when said switch is opened.

7. In combination, a supply circuit, a transformer, a translating device, a switch adapted to connect the transformer primary to the supply circuit, a second switch adapted to connect the transformer secondary to the device, a magnet winding for operating the first switch, and contacts in circuit with said magnet winding controlled by the second switch, said contacts being arranged to be closed before and opened after the main contacts of the second switch are closed and opened.

8. In combination, a supply circuit, a transformer, a translating device, an automatic switch for opening the circuit between the transformer and the supply circuit, a second switch adapted to connect the transformer secondary to the translating device, an electromagnet for closing said automatic switch, and auxiliary contacts on said second switch for controlling the circuit of said electromagnet, said contacts being arranged to be closed before and opened after the main contacts of the second switch are closed and opened.

In witness whereof I have hereunto set my hand this 21st day of June, 1906.

MATTHEW O. TROY.
